UNITED STATES PATENT OFFICE.

ROBERT M. COX, OF PHILADELPHIA, PENNSYLVANIA.

DESIGN FOR A VAULT-LIGHT.

SPECIFICATION forming part of Design No. 33,139, dated August 28, 1900.

Application filed July 5, 1900. Serial No. 22,639. Term of patent 14 years.

To all whom it may concern:

Be it known that I, ROBERT M. COX, of the city and county of Philadelphia, in the State of Pennsylvania, have invented a new and original Design for a Vault-Light, of which the following is a specification.

My design for vault-lights is shown in the accompanying drawing, which is a perspective view of a vault-light embodying the same.

The vault-light consists of a single lower extended prism *a*, depending from a horizontal top *b*, provided on its upper surface with a series of concave grooves *c*, extending trans-

versely to the prism *a*, said concave grooves meeting in a series of transverse ribs *d*. 15

What I claim as new, and desire to secure by Letters Patent, is—

The design for a vault-light substantially as described and as shown in the accompanying drawing. 20

In testimony of which invention I have hereunto set my hand.

ROBT. M. COX.
